UNITED STATES PATENT OFFICE.

REUBEN A. McCUALEY, OF BALTIMORE, MARYLAND.

ODORLESS EXCAVATING APPARATUS.

SPECIFICATION forming part of Letters Patent No. 373,938, dated November 29, 1887,

Application filed June 25, 1887. Serial No. 242,535. (No model.)

To all whom it may concern:

Be it known that I, REUBEN A. McCUALEY, a citizen of the United States, residing at Baltimore, in the State of Maryland, have invented certain new and useful Improvements in Odorless Excavating Apparatus; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to apparatus which is employed in the excavation and cleansing of sinks, vaults, and other places where offensive and dangerous gases are likely to arise and be disseminated during the process of excavation; 20 and it consists in providing a specially-designed folding tent which may be placed in such position about the vault or sink to be operated upon that the entire apparatus and operation may be concealed from view; and 25 my invention further consists in providing a specially - designed deodorizer which is suspended inside of the tent, whereby the escaping gases, both those from the deodorizer and the offensive gases from the sink, will be caused 30 to mingle as they escape to the atmosphere, and the offensive gases rendered odorless and harmless, the whole apparatus being so constructed that it may readily be placed in position for operation or removed and folded into 35 a small space for convenience of transportation.

In the further description of my invention reference is had to the accompanying drawings, in which—

40 Figure 1 is a front elevation of the tent, partly in section. Fig. 2 is aside elevation in section of the device complete. Fig. 3 is a detailed front elevation, partly in section, of the deodorizer. Fig. 4 is a detailed side elevation, 45 partly in section, of the deodorizer. Fig. 5 is a detailed view of the folding frame, showing construction of cross-beams.

The same figures refer to the same or similar parts throughout the several views.

50 The figure 6 denotes the folding tent, which in Fig. 2 is represented attached to a privy, 7, in which the excavating or cleaning is to be

performed, the tent 6 forming an inclosure around that part of the privy in which is the door or opening 8. The said tent 6 is constructed with a folding frame, which consists of the uprights 9, to which is hinged, by means of an eyebolt, 10, and hook 11, the arm 12, which by this method of securing may be folded close to the upright 9. The free ends 55 of these arms 12 are each provided with a cross-beam, 13, which meet and overlap one another, Fig. 5, and are held together by an eyebolt, 14, in such manner as to permit a fold of these two cross-beams 13 to be made at this 60 point, a pin, 15, being provided, which passes through both beams 13 when it is desired to hold them in the extended position.

The upper end of the upright 9 is provided with two cross-beams, 16, which meet and overlap in the same manner as those described on the free ends of the arms 12, the eyebolt 17 serving as a pivot and to secure the said cross-beams 16, a pin, 15½, being provided to hold them in the extended position, as in the case 75 of those beams on the arm 12. When in position for operation, the arm 12 is held extended by means of the rod 18, which is provided with an eye, 19, at one end thereof, by which it is secured to the eyebolt 14, the other end of the 80 said rod 18 being provided with the hook 20, by which it may be readily secured in the eyebolt 17.

The structure is secured in its proper position by resting the uprights 9 upon the ground 85 and securing the upper portion thereof by means of a rope, 21, which may be made fast to a nail or hook, 22, temporarily secured to some suitable part of the privy. The entire frame, with the exception of that part which 90 adjoins the privy 7, is covered with a canvas covering, 23, sufficient space being afforded therein to perform all the operations of excavation, the frame and its cover 23 being drawn sufficiently close to the privy 7 to prevent the 95 escape of any gases except through the opening 24 in the cover 23, which is provided for this purpose.

In order to render the escaping gases odorless and harmless the deodorizer 25 is provided 100 and suspended from the rod 18 by its bail 26, the said deodorizer 25 consisting of the casing 27, in which is placed a lamp, 28, which may be of common construction and has a thumb-

screw, 29, for the adjustment of the flame. The chimney 30 is constructed of sheet metal and has an aperture, 31, therein, which is protected with isinglass, in order that the flame 32 may be observed for proper adjustment. Supported on the chimney 30, in such manner that the heat from the flame 32 will impinge thereon, and at the same time afford sufficient ventilation for the said flame, is the evaporating-pan 33, which serves to evaporate the deodorizing-mixture (carbolic acid or any suitable disinfectant) as it is dropped from the reservoir 34, which is secured to some part of the deodorizer 25 above the evaporating-pan 33, and is provided with the cock 35, whereby the quantity of disinfecting material supplied to the evaporating-pan 33 may be controlled, the gases from the deodorizer, when they are set free, mingling with the gases from the sink in their escape through the opening 24, whereby the offensive gases will be disinfected and rendered odorless and harmless.

The manner of operating is as follows: In Fig. 2 is represented a cask, 36, which has an opening provided with a hermetically-sealing cap, in order that no gases may escape from the cask when being transported. The tent 6, as represented in Fig. 2, may be made sufficiently large to afford room inside for this cask 36 and the operators to perform the necessary work, which is done with the bucket 37 by dipping the soil from the sink and pouring into the cask 36. The deodorizing apparatus having been put in operation by lighting the lamp 28 and adjusting the cock 35 so that sufficient of the disinfecting material may be caused to drop upon the evaporating-pan 33 and be evaporated in the manner heretofore described, these disinfecting gases from the evaporating-pan 33 pass through the opening 24 and sufficiently mix with the gases from the sink to disinfect the latter and render them odorless. When the cask 36 is filled, its hermetically-sealed cap is placed thereon, 45 when the cask may be removed, another substituted, and the operation continued until the work is completed.

I do not, however, confine myself to the use

of the cask 36 in the tent 6 and the employment of the dipper or bucket 37 for dipping 50 the soil, as the tent and deodorizer may be employed with equal advantage when a pump is used and the soil raised by suction and forced into the cask 36 or a tank, as is now commonly done. In this latter operation, 55 though a deodorizer is placed over the vent of the transporting-vessel, a great evil still exists in the offensive gases which arise from the sink, caused by and during the process of pumping. By placing the tent 6 around the door 8 of privy 7, with the deodorizer 25 therein, this defect will be remedied and the offensive gases from this source be rendered odorless and harmless, in the manner heretofore described. 65

There may be occasions when it would not be practicable to employ the tent 6, in which case a pump can be used for excavating, as in common use, and the opening 8 in the privy 7 closed, a vent being formed in some convenient part of the privy, and the deodorizer 25, herein described, is placed within the privy 7, whereby the escaping gases from this source will deodorize in the manner described.

Having described my invention and the manner of operating, what I claim, and desire to secure by United States Letters Patent, is—

In an odorless excavating apparatus, the combination of a tent or screen, 23, provided with an opening, 24, at its top, and a deodorizing-stove, 25, consisting of the casing 27, the bail 26, the lamp 28, the evaporating-pan 33, the chimney 30, and a reservoir, 34, provided with the cock 35, the said deodorizing-stove 25 being suspended within the said tent 23, 85 whereby a current of air is created through the said opening 24 by the heat from the said deodorizing-stove and the heated disinfecting-gases arising therefrom, for the purpose set forth. 90

In testimony whereof I affix my signature in presence of two witnesses.

REUBEN A. McCUALEY.
